UNITED STATES PATENT OFFICE.

ARTHUR A. BLANKENMEISTER, OF ST. LOUIS, MISSOURI.

DESIGN FOR A PLATE OR SIMILAR ARTICLE.

40,963.

Specification for Design.

Patented Nov. 1, 1910.

Application filed August 1, 1910. Serial No. 575,033. Term of patent 7 years.

To all whom it may concern:

Be it known that I, ARTHUR A. BLANKENMEISTER, a citizen of the United States, residing at St. Louis, in the State of Missouri, have invented a new, original, and ornamental Design for a Plate or Similar Article, of which the following is a specification, reference being had to the accompanying drawing, forming part thereof.

The figure is a plan of a plate or similar article having my design thereon.

I claim:

The ornamental design for a plate or similar article, as shown.

ARTHUR A. BLANKENMEISTER.

Witnesses:

E. E. LONGAN,
E. L. WALLACE.
